CLAIM

The ornamental design for a radial heat sink, as shown and described.

DESCRIPTION

FIG. 1 is a top perspective view of an embodiment of a radial heat sink, showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof; and,

FIG. 8 is a right-side view thereof.

The broken lines illustrate portions of the radial heat sink that form no part of the claimed design.
